(57) **CLAIM**

The ornamental design for an illuminated ring, as shown and described.

DESCRIPTION

FIG. 1 shows a perspective view of an illuminated ring; FIG. 2 shows a front view of the illuminated ring; FIG. 3 shows a rear view of the illuminated ring; FIG. 4 shows a right side view of the illuminated ring; FIG. 5 shows a left side view of the illuminated ring; FIG. 6 shows a top plan view of the illuminated ring; and, FIG. 7 shows a bottom plan view of the illuminated ring. The shade lines in the Figures show contour and not surface ornamentation.

The broken lines shown in the Figures show portions of the illuminated ring which form no part of the claimed design.

1 Claim, 4 Drawing Sheets
